UNITED STATES PATENT OFFICE

BERNICE J. NOYES, OF BOSTON, MASSACHUSETTS.

MUNICIPAL SIGNAL APPARATUS.

SPECIFICATION forming part of Letters Patent No. 447,061, dated February 24, 1891.

Application filed September 14, 1888. Serial No. 285,365. (No model.)

To all whom it may concern:

Be it known that I, BERNICE J. NOYES, of Boston, county of Suffolk, State of Massachusetts, have invented an Improvement in Municipal Signal Apparatus, of which the following description, in connection with the accompanying drawing, is a specification, like letters on the drawing representing like parts.

In another application filed by me concurrently with this, Serial No. 285,354, a municipal telegraph system is shown adapted for police-signal purposes, wherein several sub-stations and a central station are connected by an electric circuit. In said application the 15 different signals were transmitted over a metallic circuit, and an instrument capable of producing or transmitting impulses or currents of a different character was included in another circuit, preferably formed by ground 20 taps or branches between the metallic circuit. The instrument therein shown was what is commonly known as a "magneto-electric generator."

In this my present invention the signals are 25 transmitted over a metallic circuit, and induced impulses are employed to operate or call into operation the audible alarm or indicating signal. The induced impulses are produced by induction-coils, which are included 30 in local-battery circuits including a circuit-changing device, also the secondary coils are included in the main circuit. A polarized receiving-instrument is located at the central station, which is responsive to the said induced impulses. The code-signal transmitter 35 in the box at the sub-station may be any usual or suitable form of multiple-signal transmitter, the form herein shown being substantially that contained in United States 40 Patent No. 320,032, dated June 16, 1885, it comprising several signal-wheels on a shaft, a series of pens, one for each signal-wheel, and a selecting-cylinder constructed and arranged 45 to press one or another pen into engagement with the signal-wheels, a pointer for rotating the selecting-cylinder, and a dial for the boxes over which the pointer moves. Telephones are provided arranged in ground-taps of the 50 main circuit, which will be employed in usual manner.

The drawing shows in diagram a multiple-signal transmitter, induction-coil, and tele-

phonic instruments, and the circuits at the sub-station, and also the signal-receiving instrument, polarized instrument, and audible alarm 55 or indicating signal, and the telephonic instruments and circuits at the central office or main station. At the sub-stations multiple-signal transmitters are employed of any well-known form or construction, the multiple-signal transmitter herein shown being of the kind shown in patent referred to, it comprising a series of signal-wheels $a a' a^2 a^3$, a series of pens $b b' b^2 b^3$, and a selecting cylinder and pointer. (Not shown.) The multiple-signal transmitter is 60 included in a main electric circuit A, which includes the main battery A', and at the main or central station a receiving-relay c is employed, the armature of which controls a local circuit c' containing a battery c'' and a register R. The signal-wheels $a a' a^2 a^3$ are so formed as to effect the transmission of different signals in conjunction with the box number, and the receiver R is designed to receive 65 all the signals transmitted.

In United States Patent No. 359,687, dated 70 March 22, 1887, heretofore granted to me, a municipal telegraph system is shown comprising a main or central station and several 75 sub-stations connected by an electric circuit, the sub-stations containing signal-transmitters, and the main station containing a signal-receiver, and also an audible alarm or indicating signal, which is responsive to some 80 of the signals transmitted, but not others.

In accordance with this invention an audible alarm or indicating signal is provided at the main or central station, which is responsive to some of the signals transmitted, and to effect this result an induction-coil B is placed 85 at the sub-station, the primary coil p of which is included in a local circuit p' containing the battery p'' and the circuit-wheel a^4 and pen b^4 , while the secondary coil s is included 90 in the main electric circuit.

For simplicity of operation I have placed the circuit-wheel a^4 upon the same shaft with the wheels $a a'$, &c., but insulated therefrom, and I have secured the pen b^4 to the same block to which the pens $b b'$, &c., are attached, 100 and the contact portions of the circuit-wheel are arranged with relation with the contact portions of the other wheels, so as not to interfere in operation, but to operate in con-

junction with some of the wheels, so that induced impulses may be transmitted in advance of or immediately after the signals with which it is to co-operate. At the central station a polarized receiving-instrument is employed which is included in the main electric circuit and responsive to induced impulses.

As herein shown, the polarized instrument is a relay, as R' , the armature of which controls the electro-magnet m included in a local-battery circuit m' , and the armature of said electro-magnet m in turn controls the drop m^2 in a local-battery circuit m^3 , which includes a bell.

It is obvious that the armature of the relay R' may be provided with a bell-hammer and directly tap the bell.

I have shown the circuit-changer b^4 as formed with four contact portions to transmit four induced impulses, yet any other number of contact portions may be provided.

At the main and sub stations ground taps or branches n lead from the main circuit in which the telephonic instruments t are included in any usual or suitable manner.

I claim—

1. In a municipal telegraph system, a main station and several sub-stations connected by an electric circuit, multiple-signal transmitters at the sub-stations, and signal-receivers at the main station, combined with an inductorium one of the coils of which is included in the main signaling-circuit and the other coil in a battery-circuit, a circuit-changer for said battery-circuit, which operates automatically in conjunction with some signals and not others, and a polarized receiving-instrument at the main or central station responsive to the induced impulses, substantially as described.

2. In a municipal telegraph system, a main station and several sub-stations connected by an electric circuit, a multiple-signal transmitter at the sub-stations comprising a series of signal-wheels and a series of pens, and a signal-receiving apparatus at the main station responsive to the changes in the condition of the main circuit produced by said multiple-signal transmitter, combined with an inductorium one of the coils of which is included in a main circuit and the other in a local-battery circuit, a circuit-wheel a^4 , fixed to and insulated from the rest of the shaft carrying the signal-wheels, the pen d^4 , and the polarized receiving-instrument at the main station responsive to the induced impulses, substantially as described.

3. In a municipal telegraph system, a main station and several sub-stations connected by an electric circuit, a multiple-signal transmitter at the sub-station, and a signal-receiving apparatus at the main station responsive to the changes in the condition of the circuit produced by said multiple-signal transmitter, combined with an inductorium at each sub-station, one of the coils of which is included in said circuit and the other coil in an independent battery-circuit, a circuit-changer for making and breaking said independent battery-circuit which is operated automatically in conjunction with some signals but not others, and a polarized signal-receiving apparatus at the main station responsive to the induced impulses, substantially as described.

In testimony whereof I have signed my name to this specification in the presence of two subscribing witnesses.

BERNICE J. NOYES.
